UNITED STATES PATENT OFFICE.

JUDSON SWITZER, OF PORTLAND, OREGON.

GAGE.

1,223,531.

Specification of Letters Patent. Patented Apr. 24, 1917.

Application filed July 13, 1916. Serial No. 109,110.

To all whom it may concern:

Be it known that I, JUDSON SWITZER, a citizen of the United States, residing at Portland, in the county of Multnomah and State 5 of Oregon, have invented certain new and useful Improvements in Gages; and I do declare the following to be a full, clear, and exact description of the invention, such as will enable others skilled in the art to which 10 it appertains to make and use the same.

This invention relates to new and useful improvements in gages, and more particularly to gages which are adapted for use by carpenters, and the primary object of the 15 invention is to provide a simple device of this character designed to quickly and accurately locate on a door the exact point at which to cut the opening for the lock, and also to locate the opening for the face plate 20 in the frame, and the width and depth of the cuts for the hinges.

Another object of this invention is to provide a device of this character which is simple and durable in construction, inexpensive 25 to manufacture, and one which will be very efficient in operation.

With these and numerous other objects in view, the invention consists of the novel 30 features of construction, combination and arrangement of parts which will be herein referred to and more particularly pointed out in the specification and claims.

In the accompanying drawing:

Figure 1 is a top plan view of the gage; 35 Fig. 2 is a vertical longitudinal section taken on the line 2—2 of Fig. 1;

Fig. 3 is a horizontal section taken on the line 3—3 of Fig. 2;

Fig. 4 is a vertical transverse section on 40 the line 4—4 of Fig. 3;

Fig. 5 is a vertical transverse section on the line 5—5 of Fig. 3;

Fig. 6 is a similar view taken on the line 6—6 of Fig. 3;

Fig. 7 is a view of one end of the gage;

Fig. 8 is a view of the opposite end of the same; and Fig. 9 is a detail perspective of one of the nut members.

Figs. 10 and 11 are diagrammatic views 50 showing the method of operating the gage when the same is applied to a door or door jamb to gage the correct width of the hinge leaves;

Fig. 12 shows the operation of the projecting spur at one end of the gage to de-

termine the correct depth of the cut to receive the leaves;

Figs. 13 and 14 are diagrammatic views showing the method of applying the gage to use for determining the width of the lock 60 recess in the door, and the latch plate opening in the door jamb respectively;

Fig. 15 is a detail perspective view on one of the spurs.

In describing my invention, I shall refer 65 to the drawing in which similar reference characters designate corresponding parts throughout the several views and in which the numeral 1 designates a casing which is formed of two substantially rectangular 70 plates 2 and 3 which are superposed, and have at their opposite end edges each a laterally projecting flange 4 or 5 which form end walls for the casing. The end flange 5 which projects upwardly from the bottom 75 plate which is designated by the numeral 3 extends a predetermined distance above the top plate 2 to form a guide flange 6, the purpose of which is obvious in devices of 80 this character. The plates 2 and 3 of the casing are connected at their sides by substantially U-shaped bars 7 which have their arm portions secured to the lower surface of the top plate 2 and the upper surface of the bottom plate 3, adjacent the edges of the 85 same respectively. These connections are riveted as designated by the numeral 8. These U-shaped bars 7 form the side walls 90 for the casing 1, and the base portions of the same will be positioned within the casing 95 back from the side edges of the same.

The plates 2 and 3 have extending from one end of the same longitudinally extending slots 9, which are positioned in vertical alignment, and may if desired have a graduated 95 scale 10 adjacent one of their edges. These slots 9 form guides for spurs 11 projecting outwardly through the same, for a purpose to be hereinafter more fully described.

Positioned within the casing 1 and extending longitudinally in the same are a pair of screws 12 and 13, the screw 12 having its opposite ends swiveled in the end walls 4 and 5 of the casing, while the screw 13 has one end swiveled in the wall 5 of the 105 casing, while its opposite end is mounted in a bearing block 14 adjacent the opposite end of the casing. The end portions of the screws 12 and 13 project through the wall 5 of the casing, and are provided with slots 110

15 therein to receive a screw driver, or any other tool whereby the screws may be rotated.

Positioned on the screws 12 and 13 within the casing are nut members 16 which project inwardly, and have portions 17 thereof directly between the slots 9 in the upper and lower plates of the casing. These portions 17 of the nut members are recessed as shown at 18, and are adapted to receive the spurs 11 which have forked or split lower ends 19 disposed within these recesses. These spurs 11 are adjustably held in position by means of set screws 20 which project through the split ends of the spurs, and are positioned in apertures 21 in the recesses. The portions 17 of the nut member 16 are provided with these spurs at the top and bottom of the same, so that the spurs will project in pairs through the slots in the top and bottom plates. These nut members 16 are threaded and are operatively engaged by the screws 12 and 13, so that upon rotation of the screws in either direction, the nut members and spurs will be moved along the slots accordingly. By this means the spurs may be adjusted according to the different measurements desired.

At the end wall 4 of the casing 1 is positioned another short length screw 22 which has one end swiveled in and projecting through said end wall, while its opposite end is positioned in the outer side of the bearing block 14. The projecting end of the screw 22 is provided with a slot, so that it may be engaged by a screw driver or any other tool to rotate the same. Positioned on the swiveled screw 22 is an inwardly extending nut member 23, which is operatively engaged therewith, and the inner end of said member is bent parallel with said screw as shown at 24 and projects through an opening 25 in the wall 4 of the casing. Positioned on the extremity of the projecting portion 24 of this member is a spur 26. It will be obvious from this arrangement that upon rotation of the screw 22 the nut member 23 will be moved accordingly, and the spur 26 will be adjusted toward and from the end wall of the casing. This spur 26 as well as the spurs 11 which move within the slots 9, are detachably connected, so that they may be easily removed and replaced when the original spur is worn.

From the above described construction and arrangement of parts it will be seen that I have provided an extremely simple gage of this character which is adapted for quickly and accurately locating in a door the exact points at which to cut the openings for the lock. This gage is also adapted to locate the points at which to cut the opening for the adjacent face plate in the frame, and also the width and depth of the cuts for the hinges. When the gage is used to de-

termine the correct width of hinge leaves, as shown in Figs. 10 and 11 of the drawings, the same engages the door A as clearly shown in Fig. 10, with the flange positioned against one side of the door, and one of the spurs correctly adjusted so as to score the edge of said door according to the width of the hinge leaf. In Fig. 11, the gage is positioned in the door jamb B in such a manner that the flange will be within the recess portion of the jamb, and it will be obvious that there will be a slight difference between the two widths, owing to the projecting flange, this width being sufficient to prevent the door from binding. It will be understood that the spurs which determine the width of the leaf are adjusted the same for engaging the door and jamb; consequently the slight difference is caused by the flange.

In Fig. 12, the operation and use of the projecting spur 26 at one end of the same is illustrated. This spur is adjusted to determine the correct depth of the cut to receive the hinge leaf, and the same is engaged with the door jamb B as clearly shown in the figure, but it is obvious that it can equally as well engage the door A to determine the correct depth to be cut away to form the hinge receiving recess.

Figs. 13 and 14 are diagrammatic views showing the use of the gage at the opposite side of the door, Fig. 13 showing the gage in position to determine the width of the lock receiving recess, while in Fig. 14 the gage is positioned to determine the width of the latch plate opening. When used to gage the latch receiving recess the gage is positioned against the door A with the flange engaging one side of the same, and the spurs correctly adjusted to the desired width. The gage is then operated to score the edge of the door in parallel lines the required distance apart. This same operation is repeated in applying the device to the door jamb B, only in this instance the flange is positioned within the recess, thus creating a slight difference in the positioning of the gage and lines scored thereby which will give a sufficient play so as to prevent the door from binding when in operation. The various means of adjusting the spurs which project through the slots in the top and bottom plates of the casing, and the spurs which project from one end of the same have been hereinbefore described, and the method of operating the same is obvious.

I claim:

1. A device of the class described comprising a casing having a slot in one side thereof, a screw swiveled in said casing adjacent one side of the slot, a nut member on said screw having one flat side thereof extending transversely across the slot, a spur detachably connected with the portion of the member

adjacent the slot and projecting through said slot, one end of said screw being adapted for engagement with operating tools.

5. 2. A device of the class described comprising a casing having a slot in one side thereof, a screw swiveled in said casing adjacent one side of the slot, a nut member on said screw having one flat side thereof extending 10 transversely across the slot, the portion of the member adjacent the slot having a recess therein, a spur extending through the slot and having a bent forked end adapted to be positioned in said recess, and fastening 15 means carried by said member and positioned between the forked end of said spur to removably fasten the same thereto.

3. A device of the class described comprising a casing having aligned slots in its top 20 and bottom, a guide flange in one end of said casing, a pair of longitudinally extending spaced screws in the casing on the opposite sides of the slots, one screw having its opposite ends swiveled in the end walls of the 25 casing and the remaining screw having one end swiveled in one end wall and the other in a bearing block adjacent one end of said casing, and members on the screws having portions positioned between the slots, spurs 30 on the members projecting through the slots and tool engaging means in the ends of the screws.

4. A device of the class described comprising a casing having aligned slots in its top 35 and bottom, a guide flange on one end of said casing, a pair of longitudinally extending spaced screws swiveled in said casing on opposite sides of the slots, nut members on the screws having portions positioned between the slots, spurs on 40 said portions projecting through said slots, and tool engaging means in the ends of the screws.

5. A device of the class described comprising a casing, a guard flange at one end of the same, a screw swiveled in said casing, a 45 nut member on the screw having a project-

ing portion bent parallel with said screw and extending through the adjacent end of the casing, a spur on said projecting end, and tool engaging means in one end of the 50 screw.

6. A device of the class described comprising a casing, a guard flange at one end of the same, a screw having one end swiveled in one end wall of the casing and the other 55 end in a bearing block adjacent the same, a nut member on said screw, a projection on the nut extending parallel with the screw and projecting through the end wall of said casing, a spur detachably connected to the 60 extremity of said projection, and the end of said screw projecting through the casing and having tool engaging means therein.

7. A device of the class described comprising a casing formed of a pair of superposed 65 plates having slots therein, flanges on the end edges of the plates to form end walls between the same, one end extending beyond the adjacent plate, bars connecting the plate to form side walls, spurs projecting from 70 said slots, and means to move said spurs along the slots in the casing.

8. A device of the class described comprising a casing formed of a pair of substantially rectangular-shaped superposed plates 75 having slots therein, inwardly projecting flanges on the opposite end edges of said plates forming end walls for said casing, one flange extending beyond the adjacent plate, substantially U-shaped bars positioned between the plates and having their arm portions secured to the same adjacent the side edges, spurs projecting from the slots in the plates, and means in the casing to move said spurs.

In testimony whereof I have hereunto set my hand in the presence of two subscribing witnesses.

JUDSON SWITZER.
